DESIGN FOR A SPORT STOCKING

Gaetano Emilio Piana, Brentwood, N. Y.

Application December 6, 1943, Serial No. 111,929

Term of patent 14 years

(Cl. D47—7)

To all whom it may concern:

Be it known that I, Gaetano Emilio Piana, a subject of Italy, residing in Brentwood, county of Suffolk, and State of New York, have invented a new, original, and ornamental Design for a Sport Stocking, of which the following is a specification, reference being had to the accompanying drawing, forming part thereof.

The figure of the drawing is a perspective view of a sport stocking showing my new design.

I claim:

The ornamental design for a sport stocking, as shown.

GAETANO EMILIO PIANA.
